UNITED STATES PATENT OFFICE.

JOHN LAWSON, OF PAWTUCKET, RHODE ISLAND, AND EVERETT A. QUINT, OF NEW BRUNSWICK, NEW JERSEY, ASSIGNORS TO HEMPHILL COMPANY, OF CENTRAL FALLS, RHODE ISLAND, A CORPORATION OF MASSACHUSETTS.

SPRING-BEARD KNITTING NEEDLE.

Original application filed July 24, 1923, Serial No. 653,457. Patent No. 1,500,627, dated July 8, 1924.
Divided and this application filed April 8, 1924. Serial No. 705,137.

To all whom it may concern:

Be it known that we, JOHN LAWSON and EVERETT A. QUINT, citizens of the United States, and residents, respectively, of Pawtucket, county of Providence, and State of Rhode Island, and of New Brunswick, county of Middlesex, and State of New Jersey, have invented an Improvement in Spring-Beard Knitting Needles, of which 10 the following description, in connection with the accompanying drawings, is a specification, like characters on the drawings representing like parts.

This application is a division of our co-pending application Serial No. 653,457, filed July 24, 1923 Patent No. 1,500,627 of July 8, 1924.

This invention relates to spring beard knitting needles and to a knitting organization including such needles.

In order that the principle of the invention may be readily understood, we will describe the preferred embodiment of the needle and its manner of use, and will sufficiently 25 describe the method of making the needle to give a complete statement of the construction of the needle and its advantages.

In the drawings,—

Fig. 1 is a side elevation, twice enlarged, 30 of a steel wire which has been swaged or reduced until the intermediate part thereof has been reduced to a smaller diameter and one end has been reduced to a still smaller diameter;

Fig. 2 is a view similar to Fig. 1, but representing the upper or smaller end of the blank as milled or otherwise beveled or reduced to a still smaller diameter preparatory to forming a spring beard thereat;

Fig. 3 is a view similar to Fig. 2, but representing the beard as completed;

Fig. 4 is a view of the retained lower part only of the needle blank and representing the same as bent to provide material for the 45 butt that is to operate in the cam groove of the cam ring;

Fig. 5 is a side elevation, three times enlarged, of the needle blank after it has been flattened, but before the lower end and butt 50 have been trimmed;

Fig. 6 is a view similar to Fig. 5 but representing the needle as completed, excepting for a lateral bending which may be resorted

to in order to provide sufficient friction in the needle grooves of the needle cylinder;

55

Fig. 7 is an edge view of the needle shown in Fig. 6 and representing the same as slightly laterally bent to provide for friction in its groove of the needle cylinder;

Fig. 8 is a plan view on the scale of Figs. 60 5 and 6 and showing the parts that are trimmed off; and

Fig. 9 is a detail partly in vertical section and partly in interior elevation representing a few of the needle butts in the cam 65 groove.

Spring beard needles are old and well known in the art; in fact the needles of the first knitting machine were spring beard needles. For more than one hundred years 70 all knitting machine needles were of the spring beard type, as it was not until toward the middle of the nineteenth century that the latch needle was invented by Matthew Townsend. Spring beard needles both 75 of the independent type and of the fixed type, are also well known, and at the present day there is an increasing demand for spring beard needles of fine gauge and of the independent type. At the present time, 80 such fine gauge, spring beard needles of the independent type are bent at their lower ends or at some intermediate part, so as detachably to engage a jack which itself is provided with a butt to be received in and 85 operated by the walls of the cam groove of the cam ring. Such a jack is preferably laterally bent so as to give it sufficient friction to retain its position in the needle groove and the butt thereof is of relatively great 90 height so as properly to operate in the said cam groove of the cam ring. Attempts have even been made to shape by bending the lower or some intermediate part of the stem of the 95 spring beard needle of the independent type into a butt of U form, which butt was to be received in the cam groove of the cam ring. Such a needle, so far as we are aware, has never been commercially acceptable or satisfactory, and in all such cases of which we 100 are aware, the stock of the butt was of the same diameter as the stem of the needle, or at least of the main lower part of the stem of the needle.

So far as we are aware, no one has ever 105 produced or attempted to make a spring

beard needle of the independent type of substantially the form shown in Fig. 6 and which, as a characteristic feature thereof, is provided with an integral butt to enter the 5 cam groove of the cam ring, said butt being flattened from the stock of the blank, which in the course of the operation is left of sufficient diameter to provide for the relatively 10 large butt characteristic of the needle of our invention.

The needle of our invention overcomes the objections to the spring beard needles of the prevailing type now upon the market in that we avoid the necessity of forming a separate 15 jack for each needle and bending the needle to conform to the shape of and to engage a suitable notch or recess of the jack. Inasmuch also as the needle of our invention is of one integral piece, there is no possibility 20 of slippage or relative displacement, such as may occur between the usual spring beard needle and its jack.

We are aware that latch needles have long been provided with integral butts to be received 25 in and operated by the cam groove of the cam ring. A latch needle is, however, radically different in many and well known ways from a spring beard needle. The parts which cooperate with the spring beard 30 needle and the latch needle in the formation of the stitch are wholly different, and the processes or steps to which the needles of these two types must be subjected during formation are wholly and radically different.

35 In the drawings, we have represented the several steps or stages in the manufacture of the spring beard needle of our invention according to the best mode now known to us for making the same. Certain of the 40 steps may be modified or changed without departing from the principles of our invention as an entirety, and certain of these changes will be hereinafter referred to.

For the needle of our invention we employ 45 what is known as steel needle wire, such wire being of cast steel and annealed. It is known upon the market as spring beard needle wire and is purchased in coils of uniform diameter or size. The coils are annealed, and all 50 the steps of the process hereinafter described are carried out with the wire in its annealed condition. After the needle is completed, it is then tempered in oil. Such wire is cut 55 into a suitable length, depending upon the desired length of the needle, and then it is swaged or otherwise suitably reduced in diameter desirably at two spaced points indicated at 1, 2 in Figs. 1, 2 and 3. This provides three portions A, B, C. A part of 60 the portion C is afterward to be cut off, as indicated by the dotted line X in Fig. 3, according to the disclosed embodiment of the invention to which we are not necessarily limited, but during the early stages of manufacture the portion C is of the relative length

indicated, so as to provide herein a handle for convenience of manipulation.

The end of the portion A is still further reduced in diameter in one dimension preferably by a suitable milling operation, as by 70 clamping a number of the blanks in a holder and subjecting them to the action of a suitable milling tool, so as to reduce the stock to a proper diameter in such dimension preparatory to the "rounding up" or grinding 75 and tapering operation preliminary to the formation of the beard indicated at 3 in the several figures.

After the said milling operation, the blanks are treated individually by subjecting 80 the milled portion thereof to a grinding operation for the purpose of "rounding up" that portion of the blank, and at the same time tapering the same gradually to a point, so as to provide the proper shape preparatory 85 to the bending of the end to form the beard 3, and so as to give the necessary smoothness to the blank following the milling operation. In order to grind and thereby taper each blank, it is highly important 90 that the blank be of cylindrical shape throughout, or in other words that it be not yet subjected to the bending operation initially to form the butt or to the butt-flattening operation, because the blank 95 could not then be held in the hand and turned constantly with the necessary delicacy of touch which is requisite to forming the beard of the proper taper. It will be understood that the formation of the beard 100 of the proper taper is of extreme importance, as if this step of the operation be improperly carried out, the needle will not be of the proper gauge and must be rejected. It will be understood that the "rounding 105 up" or grinding with tapering does not remove the flat effect resulting from the milling, but does remove the edges or corners thereof. On the contrary, the upper or milled end of the blank is flat, but also of 110 a generally tapering formation and particularly at or toward the point 5.

At some suitable step in the operation, the groove or so-called nucate 4 is formed into which the point 5 of the needle beard 3 is 115 pressed during or preparatory to the casting off of the stitch. Desirably this groove or "eye," as it is sometimes called, is cut or formed in the blank after the milling operation and before the grinding or rounding up 120 operation, and therefore directly after the step of the operation indicated in Fig. 2.

It will be observed from the sections upon Figs. 1, 2 and 3 that the wire or material of the blank is round excepting at the 125 milled portion. After the needle has been brought to the form shown in Fig. 3, the handle part of the portion C is cut off, in accordance with the disclosed embodiment of the invention, as at the dotted line X in 130

Fig. 3, so as to provide merely sufficient length for the butt, which in its preliminary shape is represented at 6 in Fig. 4. The cutting off of a handle part of the portion C and the bending of the retained lower part to form the butt 6 may precede or follow the formation of the needle beard 3, but desirably it follows the same.

The needle blank, which is still of circular shape in cross section throughout its entire extent, excepting the beard portion, is now placed in a suitable press and flattened by a squeezing action, excepting for the portion of the beard above the groove, which portion is itself not subjected to such flattening operation. Such flattening should not result in any irregularity at the base of the tapered portion, as these two portions should merge smoothly into each other. The blank so flattened has now the form shown in Fig. 5 which is three times the actual size. It will be observed that the shoulder 2 is retained and that the portion B, even in its flattened condition, is relatively very slender, so that it may be bent or damaged unless handled with great care. It is, however, important that the stem of a spring beard needle be slender, and particularly that the part upon which the old loop is received below the beard be of the smallest possible diameter, so as not to subject the loop to distention.

Because of the fact that a part of the stock was left of the original diameter, it results that we have provided sufficient material for the butt which in its flattened but unfinished condition is represented at 7 in Fig. 5. It will be observed that just above the butt the lower part of the stem is enlarged both at front and rear, as indicated at 8, 9. Moreover the butt 7 is itself not of proper size, and therefore following the flattening or pressing operation, it is necessary to trim or otherwise reduce the butt 7 to exactly the right size to fit without lost motion in the cam groove of the cam ring. Furthermore the pressed and subsequently trimmed butt and lower portion of the needle stem give a much more accurate formation than can be provided by the merely bent end of a needle shank, not formed by pressing a relatively large diameter stock to flattened form.

In Fig. 9, we have indicated at 10 the cam groove of the needle cylinder, and therein represent in certain positions at 11 the needle butt in its trimmed, completed condition. It will be observed that the said butt 11 fits in said groove with a close running fit and without lost motion. This is of great and in fact of vital importance in the formation of perfect fabric. Each needle in turn is moved longitudinally in its groove in the needle cylinder by the cam groove of the cam ring, the lower wall 12

of the cam groove acting to elevate the needle to receive the yarn and the upper wall 13 of the said groove acting to depress the needle to cast off the old stitch. If the butt of the needle does not work with a close running fit in the cam groove, there would be lost motion both in the elevation and in the lowering of the needle, and this would result in inequalities and inaccuracies in the work. We have thus provided a new knitting organization including spring beard needles whose integral butts work with a close running fit in the cam groove.

We have stated that the lower ends or portions of spring beard needles have been bent upon themselves so as to enter a notch or groove of a jack which itself is provided with a butt to enter the cam groove of the cam ring. Such bent portion of the needle could not itself be used to enter the cam groove for needle manipulation because it is not of sufficient vertical extent to be operated without lost motion in such groove. Moreover such a bent portion would not prevent lateral turning or twisting of the needle with consequent defect in the formation of the loop, and furthermore such thin bent portion being of no greater diameter than the shank or stem of the needle would itself rapidly wear in two or so nearly in two as to be useless.

Obviously our improved construction, providing, as it does, an integral formation of butt and shank, has manifest advantages over a construction wherein a needle stem of the same or substantially the same diameter throughout its power part, is bent at its lower end (which is of small diameter and hence very springy), and is there received in a notch in a relatively rigid member—the jack—from which it may be easily accidentally separated, and from which it has a tendency to spring away, owing to the spring band embracing the entire series of needles.

When the needle has reached the stage represented in Fig. 5, we employ suitable means, preferably a punch and die (not herein shown) to trim the butt 7 and the lower part 8, 9 at the shank or stem to exactly the right proportions, as represented at 11, 14 in Fig. 6.

The punch and die, or other means employed for the purpose, cut off from the portion 9 at the back of the lower part of the stem a piece which is indicated at 15 in Fig. 8, and from the butt portion 7, there is cut off a characteristic U-shaped piece indicated at 16 in Fig. 8, thus leaving the needle in its completed shape shown in Fig. 6, and lacking only the very slight bending of the needle stem or shank, which may be provided in customary manner not herein necessary to illustrate. This step is desirably, but not necessarily, resorted to

for the purpose of insuring the full amount of desired friction in the needle groove. It will be observed that the flattened butt 11 is of materially greater cross section than the corresponding cross section of the greater portion of the needle stem, said butt 11 having its greater dimension in the plane of the needle stem, or in other words, in a direction which is lengthwise of the needle stem.

The removal of the parts 15, 16 leaves no burr. While we might remove the parts 15, 16 by a suitable milling process, as, for example, by clamping or holding the needles in sets and employing a suitable milling tool to mill the necessary edges, such a process would leave a burr to be removed later.

We may in certain cases, instead of drawing the needle blank to provide three diameters, provide the necessary shape by a stamping operation, for the purpose of not drawing out the material as much as according to the first method disclosed. In such case, the beard of the needle, not being so finely drawn, but being ground, is or may be tougher and stronger.

Having thus described one illustrative embodiment of the needle of our invention, we desire it to be understood that although specific terms are employed, they are used in a generic and descriptive sense and not for purposes of limitation, the scope of the invention being set forth in the following claims.

35. Claims:

1. A spring beard needle of the independent type integral throughout and having a flattened butt of materially greater cross section than the corresponding cross section of the greater portion of the needle stem, said butt having its greater dimension in the plane of the needle stem, said butt being adapted to be received directly in the cam groove of the cam ring with a close running fit.

2. A spring beard needle of the independent type integral throughout and having one extremity milled and tapered and bent to form a spring beard and at its other end having a flattened butt of materially greater cross section than the corresponding cross section of the greater portion of the needle stem, said butt having its greater dimension in the plane of the needle stem and adapted to be received directly in the cam groove of the cam ring with a close running fit.

3. A knitting organization including a cam carrier provided with a cam groove for the reception of needle butts, and a series of spring beard needles of the independent type, said needles being severally integral throughout, and each having a flattened butt of materially greater cross section than the corresponding cross section of the greater portion of the needle stem, said butt having its greater dimension in the plane of the needle stem and adapted to be received directly in the said cam groove of the cam carrier with a close running fit.

4. A spring beard needle of the independent type integral throughout and having one extremity tapered and bent to form a spring beard, the stem of the needle being of larger diameter throughout substantially its lower half than its upper half and having the extreme lower portion of still larger diameter, said needle having a flattened butt of materially greater cross section than the corresponding cross section of the needle stem excepting said extreme lower portion, said butt having its greater dimension in the plane of the needle stem, whereby said butt in its greater cross section is adapted to be received directly in the cam groove of the cam ring with a close running fit.

In testimony whereof, we have signed our names to this specification.

JOHN LAWSON.
EVERETT A. QUINT.
